UNITED STATES PATENT OFFICE.

JOHN V. RICE, JR., OF BORDENTOWN, NEW JERSEY, ASSIGNOR TO FRED. E. TASKER, OF NEW YORK, N. Y.

INTERNAL-COMBUSTION ENGINE.

937,862.

Specification of Letters Patent.

Patented Oct. 26, 1909.

Application filed September 16, 1905. Serial No. 278,735.

To all whom it may concern:

Be it known that I, JOHN V. RICE, Jr., a citizen of the United States, residing at Bordentown, in the county of Burlington and State of New Jersey, have invented certain new and useful Improvements in Internal-Combustion Engines, of which the following is a specification.

One object of the present invention is to improve the construction and mode of operation of the provisions which effect the compression necessary for operating an internal combustion gas engine.

Another object of the invention is to effect the necessary compression without having recourse to the crank case or to the cylinders in which the explosion occurs thereby obviating the well understood disadvantages which such practice entails.

Another object of the invention is to provide for running an engine of the type recited on a comparatively low grade gas and without the employment of compression means other than such as are self-contained in the engine.

Another object of the invention is to provide a self-starting multiple cylinder engine which will operate properly without a fly-wheel or at any rate with a relatively small one.

Another object of the invention is to provide a double acting engine in which the crank case is not used for effecting compression but in which unobjectionable, simple and novel means are employed for that purpose; and other objects of the invention will appear from the following description.

To these and other ends hereinafter set forth the invention comprises the improvements to be presently described and finally claimed.

The nature, characteristic features and scope of my invention will be more fully understood from the following description taken in connection with the accompanying drawings forming part hereof and in which

Figure 1, is a view principally in central vertical section illustrating portions of a multiple cylinder internal combustion engine embodying features of the invention. Fig. 2, is a rear elevational view of the cylinders shown in Fig. 1, illustrating the ports thereof. Fig. 3, is a side elevational view of the engine shown in Fig. 1, and Fig. 4, is

a view principally in central section of a single cylinder internal combustion engine embodying features of the invention and arranged for operation in connection with a drill or the like.

In the drawings I have shown cylinders each having at its extreme ends explosion chambers 1 and 2, arranged in alinement and having intermediate of its ends an enlarged compression chamber 3. Good practice and machine design dictate that the chambers 1, 2 and 3, should be internally cylindrical and that the cylindrical chamber 3, should be arranged eccentrically in respect to the chambers 1 and 2, and such a construction is therefore chosen for the purposes of illustration, but the invention is of course not intended to be limited to this particular embodiment. Arranged for coöperation with the described cylinder is a piston having its ends 4 and 5, properly fitted to the explosion chambers 1 and 2, and having an enlarged offset intermediate portion 6, properly fitted to the compression chamber 3, which construction materially shortens and lowers the center of gravity of the engine. The ends 4 and 5, and the intermediate portion 6, are shown as provided with packing rings and as externally cylindrical so as to suit them for coöperation with the parts 1, 2 and 3. Furthermore the portion 6, is shown as disposed eccentrically with respect to the parts 4 and 5.

Referring to Figs. 1 and 2, 7, is a piston rod applied to the intermediate portion of the piston and working through the compression chamber 3, so that its stuffing box or gland 8, is not exposed to an undue degree of heat and is therefore durable and easily kept tight. The piston rod 7, reciprocates a cross-head 9, in suitable ways 10, and the cross-head is connected with a link 11, by means of which rotary motion is imparted to the shaft 12, through the intervention of a crank 13. As illustrated, the cylinders comprise sections of castings suitably secured together and they may be provided with spaces as shown which constitute water jackets, and there are appropriate provisions for igniting the charges and affording means of exit for the products of combustion, all of which are too well understood to require special description. 14, 15, 16 and 17, are ports illustrated as formed within castings 18, secured to the cylinders of the

engine and they connect the ends of the compression chamber 3, of one cylinder with the explosion chambers 1 and 2, of the adjacent cylinder. The charge is of course introduced into the compression chambers as at 5 19, and 20, represents exhaust provisions.

In Fig. 4, the piston rod is arranged in the compression chamber and is shown as made in two parts 21 and 22, of which the 10 part 21, is secured to the piston and the part 22, is arranged to carry a drill or the like. 23 and 24, are the ports which may be variously and appropriately arranged.

It will be obvious to those skilled in the 15 art to which my invention appertains that modifications may be made in detail without departing from the spirit thereof, hence the invention is not limited further than the state of the art may require, but

20 Having thus described the nature and objects of my invention, what I claim as new and desire to secure by Letters Patent is:

1. In an internal combustion engine, the 25 combination with a cylinder having an eccentric compression chamber between its ends, and a piston in said cylinder having an intermediate eccentric portion fitted to said compression chamber.

2. The combination in an internal 30 combustion engine, of a pair of cylinders arranged side by side, having closed ends forming explosion chambers, and each having, intermediate between its ends, an enlarged compression chamber, pistons working 35 in the said cylinders and having their ends fitted to the said explosion chambers, and each having also an intermediate portion fitted to a compression chamber, and fluid conduits between the said compression 40 chambers and the explosion chambers, a conduit leading from one end of each compression chamber to an explosion chamber of the other cylinder.

3. The combination in an internal 45 combustion engine, of a cylinder having closed ends forming explosion chambers, and having also intermediate between its ends an eccentric compression chamber, and a piston in the said cylinder having its ends fitted to the 50 said explosion chambers and having also an intermediate eccentric portion fitted to the said compression chamber.

4. The combination in an internal combustion engine, of a cylinder having closed ends 55 forming explosion chambers, and, intermediate between its ends, an eccentric compression chamber, a piston in the said cylinder having its ends fitted to the said explosion chambers and having also an intermediate eccentric portion fitted to the 60 said compression chamber, and a piston rod connected with the said eccentric part of the piston.

5. The combination in an internal combustion engine, of a cylinder having closed ends 65

forming explosion chambers, and having also, intermediate between its ends, an eccentric compression chamber, a piston in the said cylinder having its ends fitted to the said explosion chambers and having also an intermediate eccentric portion fitted to the 70 said compression chamber, a piston rod connected with the said eccentric portion of the piston and extending through the wall of the eccentric compression chamber, and a stuffing box mounted in the said wall through which the said piston rod passes. 75

6. The combination in an internal combustion engine, of a cylinder having at its ends explosion chambers, and having intermediate of its ends an enlarged eccentric, cylindrical, compression chamber, a piston having its ends fitted to the explosion chambers and having an enlarged intermediate portion fitted to the compression chambers, ports between the compression chamber and the explosion chambers, and a piston rod applied to the enlarged portion of the piston and working through the wall of the compression 80 chamber. 85

7. The combination in an internal combustion engine, of a cylinder having at its ends cylindrical coaxial explosion chambers, and having intermediate of its ends an eccentrically arranged enlarged cylindrical compression chamber, a piston having cylindrical co-axial ends fitted to the explosion chambers and having an enlarged eccentrically arranged cylindrical intermediate portion fitted to the compression chamber, and ports between the compression chamber and 90 explosion chambers. 95

8. The combination in an internal combustion engine, of a cylinder having closed ends forming explosion chambers, and having also, intermediate between its ends, an eccentric compression chamber, a piston in the said cylinder having its ends fitted to the said explosion chambers and having also an intermediate eccentric portion fitted to the 100 said compression chamber, and direct passages between the compression chamber and the explosion chambers, the ports of which opening into the explosion chambers are controlled by the piston. 110

9. In an internal combustion engine, the combination of a pair of pistons, the opposite ends of each of which are exposed to the action of the ignited fuel charges, cylinders in which the said pistons operate, having combustion chambers beyond the ends of the pistons, and having also intermediately located enlarged eccentric compression chambers, eccentric portions on the pistons fitting into said compression chambers, and passages between the compression chambers and the explosion chambers. 120 115

10. In an internal combustion engine, the combination of a pair of pistons, arranged side by side, cylinders in which said pistons 130

- operate, having compression chambers beyond their ends, and having also intermediate located eccentric compression chambers arranged on opposite sides of the engine, eccentric portions on the pistons fitting the said compression chambers, and piston rods on opposite sides of the engine connected respectively with the said eccentric portions of the pistons.
11. The combination in an internal combustion engine, of a cylinder having closed ends forming explosion chambers, and having also, intermediate between its ends, an eccentric compression chamber, a piston in the said cylinder having its ends fitted to the said explosion chambers and having also an intermediate portion fitted to the said compression chamber, a crank shaft supported adjacent to one end of the said cylinder, a piston rod connected with the said intermediate portion of the piston and extending through the walls of the compression chamber, guides for the piston arranged adjacent to the end of the cylinder opposite the crank shaft, and a connecting rod between the piston and the crank shaft.
12. In an internal combustion engine, the

combination of a pair of cylinders arranged side by side and having closed ends to form combustion chambers, and having intermediate between the ends compression chambers arranged on opposite sides of the engine, pistons mounted in the said cylinders and arranged to move alternately, the ends of the pistons being fitted to the explosion chambers of the cylinders and having intermediate enlarged portions fitting the compression chambers, a crank shaft at one end of the engine located in proximity to the explosion chambers, piston rods connected to the said enlarged portions of the pistons and extending through the walls of the compression chambers toward the end of the engine opposite the crank shaft, and connecting rods on the opposite sides of the engine between the piston rods and the crank shaft.

In testimony whereof I have hereunto signed my name.
